DESIGN FOR A COMBINED BOTTLE STOPPER AND TOP

Tracy Higgins, Brooklyn, N. Y.

Application February 3, 1939, Serial No. 82,754

Term of patent 14 years

To all whom it may concern:

Be it known that I, Tracy Higgins, a citizen of the United States, residing at Brooklyn, in the county of Kings and State of New York, have invented a new, original, and ornamental Design for a Combined Bottle Stopper and Top, of which the following is a specification, reference being had to the accompanying drawing, forming part thereof.

The dominant feature of my design resides in the portions shown in solid lines.

I claim:

The ornamental design for a combined bottle stopper and top, substantially as shown and described.

TRACY HIGGINS.
